US00D457765S

(12) **United States Design Patent** (10) Patent No.: **US D457,765 S**
 Peotter et al. (45) Date of Patent: ** May 28, 2002

(54) **SURFACE PATTERN APPLIED TO A DISPENSER**

(75) Inventors: **Susan Marie Peotter**, Oshkosh; **Dayton Joel Henderson**, Appleton, both of WI (US)

(73) Assignee: **Kimberly Clark Worldwide, Inc.**, Neenah, WI (US)

(**) Term: **14 Years**

(21) Appl. No.: **29/129,311**

(22) Filed: **Sep. 12, 2000**

(51) LOC (7) Cl. **23-02**

(52) U.S. Cl. **D6/523**

(58) Field of Search D6/523, 515-522, D6/551; 221/282, 283; 312/34.8, 34.1; 242/570, 590, 598
